UNITED STATES PATENT OFFICE.

EDWARD PLUMHOFF, OF WAXAHACHIE, TEXAS.

HAME-HOOK.

SPECIFICATION forming part of Letters Patent No. 651,270, dated June 5, 1900.

Application filed March 7, 1900. Serial No. 7,675. (No model.)

To all whom it may concern:

Be it known that I, EDWARD PLUMHOFF, a citizen of the United States, residing at Waxahachie, in the county of Ellis and State of 5 Texas, have invented a new and useful Hame-Hook, of which the following is a specification.

This invention relates to hame-hooks; and the object of the same is to produce a device 10 of this character having a strong and durable construction, that may be quickly and easily applied to a harness-hame at either side, and to and from which a trace may be easily connected and detached.

15 The invention consists in the construction and arrangement of the several parts, which will be more fully hereinafter described and claimed.

In the drawings, Figure 1 is a perspective 20 view of a portion of a hame, showing the improved hook applied thereto in operative position. Fig. 2 is a detail perspective view of the hook, shown detached and open. Fig. 3 is an elevation of the hook, showing the members 25 fully open and in position for application to or detachment from the hame-staple or analogous device.

Similar numerals of reference are employed 30 to indicate corresponding parts in the several views.

The numerals 1 and 2 designate the members of the improved device, each of which comprises a hook 3 and 4 and an intermediate body 5 and 6. The hook 3 is positioned 35 vertically to the hook 4, and the latter has a lower rear throat 7 and the former a closing-lug 8 of a length approximately equal to and adapted to snugly fit within the said throat. The upper edge of the lug 8 is continued in 40 the same arc as the interior wall of the opening of the hook 3, and the inner opposing faces of the said hooks are flat and closely joined when pressed together, as shown by Fig. 1, and to form a circular eye, for a purpose 45 which will presently be set forth.

The body 6 of the hook 4 has the extremity 50 thereof opposite the hook provided with a pair of open knuckles 9 and 10, which are separated by a transversely-extending horizontal slot and also partially by a seat-channel 11, extending longitudinally through the inner side of the body to the rear limit of the

hook 4. The open portions of the knuckles 9 and 10 are clearly shown by Fig. 1, and between the said knuckles is an open knuckle 55 12 on the extremity of the body 5 opposite the location of the hook 1, the width and thickness of the said body being such as to permit it to snugly fit in the channel 11 of the body 6 and produce a flush joint when 60 the two members of the hook are closed, as shown by Fig. 1. By referring to Fig. 2 it will be observed that the lower edge of the body 1 has bearing in its movement on the lower wall of the channel 11, and if the position of the hook be reversed the opposite edge and wall of the channel and the body will correspondingly operate, and thus the parts or members are prevented from separating when opened, as well as when engaging the 70 vertical bar 13 of the hame-staple 14. In order to have a flush assemblage of the members of the hooks when closed, the forward upper portion of the body 6 adjacent the hook 4 is formed with an inclined shoulder 15, 75 against which the terminal of the hook 1 snugly bears and makes a flush joint with the adjacent part of the said body 6. In like manner the terminal of the hook 2 fits snugly against the one end of the lug 8 when the 80 members are closely arranged, as shown by Fig. 1, and thus the entire device is constructed without lateral projection.

In attaching the hook to a hame the members are thrown open, as shown by Fig. 3, so 85 that all the openings of the knuckles 9, 12, and 10 will be in accurate alinement. When in this position, the parts are held against accidental separation and simultaneously applied over the vertical bar 13 of the hame-staple 14 and the member 1 turned to the position shown by Fig. 2, thereby bringing the open portion of its knuckle 12 around at such an angle as to prevent accidental detachment or disengagement of the hook from the hame- 90 staple. In operating the hook to apply or detach the members the latter are never opened far enough to bring the open portion of the knuckle 12 in line with the similar portions of the knuckles 9 and 10, and a convenient 95 hinge action is thus provided without liability of separation of the members. The improved hook by its construction is made convenient for application to either hame with-

out requiring the manufacture of right and left devices, and the operation of applying a trace or tug to the improved device or removing the same therefrom is as follows:

- 5 In connecting the eye or advance link of a tug or trace to the improved device said eye or link is first passed over the terminal of the hook 3 and then moved downward to a position over the lug 8, and thus permits both members of the hook to be drawn closely together and at the same time throws or guides the eye or link of the tug or trace through the throat 7 and to pass up over the hook 3, and when said eye or link engages both hooks the latter are prevented from accidentally separating or detaching the eye or link of the tug or trace. In separating the eye or link of a tug or trace from the hook said eye or link is moved downwardly over the lug and held, 20 while the hook 3 is drawn away from the hook 4 and simultaneously moves the said eye or link of the tug or trace through the throat and permits disconnection from the hook 3.

It is proposed to make the improved hame-hook in various sizes and of suitable material, metal being preferred, and also to plate or otherwise ornament the same and to accommodate various uses or applications. Changes in the forms, proportions, and minor details 30 may be resorted to without departing from the principle or sacrificing the salient features of the invention.

Having thus described the invention, what is claimed as new is—

- 35 1. A hame-hook comprising two members having a sidewise opening and closing operation and each provided with a hook proper,

one hook having a throat through the lower portion, and the other hook formed with a lug movable into and from the said throat to make 40 a flush fitting of the two hooks when closed, the one member also having a channel to snugly receive the other member to form a close joint between said members.

2. A hame-hook comprising two side-opening members having hooks proper on one extremity of each, the opposite extremity of one member being provided with two open knuckles spaced apart from each other, and the other member having its extremity opposite 50 that on which the hook thereof is located provided with a single open knuckle movably embraced by the said two open knuckles, the open portions of all the knuckles being alined for application to and removal from a supporting device on a hame.

3. A hame-hook comprising two members having a sidewise opening and closing operation, the one member also having a pair of open knuckles and the other member a single 60 open knuckle embraced by the said pair of knuckles, the hooks of the two members closely bearing against each other when joined and the member supporting the pair of knuckles provided with a channel to snugly 65 receive the other member to make a flush fitting of the parts.

In testimony that I claim the foregoing as my own I have hereto affixed my signature in the presence of two witnesses.

EDWARD PLUMHOFF.
